DESIGN FOR WALL-PAPER.

Design No. 12,536, dated October 18, 1881.

UNITED STATES PATENT OFFICE.

EDUARD LEISSNÈR, OF NEW YORK, N. Y., ASSIGNOR TO LEISSNER & LOUIS,
OF SAME PLACE.

DESIGN FOR WALL-PAPER.

SPECIFICATION forming part of Design No. 12,536, dated October 18, 1881.

Application filed August 25, 1881. Term of patent 34 years.

To all whom it may concern:

Be it known that I, EDUARD LEISSNÈR, of New York, in the county and State of New York, have invented a new and original Design for Wall-Paper, of which the following is a specification.

This invention relates to a new and original design for wall-paper and similar fabrics; and it consists in the novel grouping and configuration of parts hereinafter more fully described.

The accompanying photograph illustrates a face view of a wall-paper having my new design.

The upper border, A, is composed of three stripes, *a b c*. The upper stripe, *a*, contains alternating diamond-shaped and hexagonal ornaments. The central stripe, *b*, is ornamented with peculiar geometrical figures, some of which represent upright ladders; others are more or less cross-like, as shown. The inner stripe, *c*, has series of upright dashes, and between them small rectangles. The lower border, B, is also composed of three stripes, *d e f*. Its upper stripe, *d*, is substantially like the lower stripe, *e*, of the border A, and the lower stripe, *f*, of the border B is very similar to the upper stripe, *a*, of the border A. The central stripe, *e*, of the border B is composed of series of obliquely-placed stripes, each of which is subdivided by lines traversing it at right angles into rectangular blocks. The main portion of the wall-

paper, which is situated between the stripes A and B, has a large central flower, D, drawn in such a way as to give it a lace-like appearance, another large flower-like figure, E, and near the same a smaller flower-like figure, F. Smaller ornaments, *g h i j*, are located between these larger figures last mentioned; but the entire design between the borders is of such uncertain outline as to more or less resemble an ornamentation inspected through a lace or curtain.

I claim—

1. The design for wall-paper, consisting of the border A, having stripes *a b c*, substantially as shown. 45

2. The design for wall-paper, consisting of the border B, having stripes *d e f*, substantially as shown.

3. The design for wall-paper, consisting of the figures D E F and ornaments *g, h, i*, and *j*, substantially as shown. 50

4. The design for wall-paper, consisting of the border A, having stripes *a b c*, border B, having stripes *d e f*, and of the figures D E F 55 and ornaments *g, h, i*, and *j*, substantially as shown.

EDUARD LEISSNÈR.
